UNITED STATES PATENT OFFICE.

WILLIAM J. McCARROLL, OF PHILADELPHIA, PENNSYLVANIA, ASSIGNOR TO BURNHAM, WILLIAMS & CO., OF PHILADELPHIA, PENNSYLVANIA, A FIRM.

MEANS FOR OPERATING VALVES OR COCKS.

No. 874,106.

Specification of Letters Patent.

Patented Dec. 17, 1907.

Application filed May 18, 1907. Serial No. 374,498.

To all whom it may concern:

Be it known that I, WILLIAM J. McCARROLL, a citizen of the United States, and a resident of the city and county of Philadelphia, State of Pennsylvania, have invented 5 certain new and useful Improvements in Means for Operating Valves or Cocks, of which the following is a specification.

My invention relates to improvements in 10 means for hydraulically operating valves or cocks and more particularly to improvements in the means for this purpose described and illustrated by me in application for United States Patent filed in the Patent 15 Office on August 17, 1906, Serial Number 330,953, and allowed December 11, 1906.

In my invention above referred to, which was designed principally with a view to draining the condensed steam from the cylinders 20 of locomotives, I made use of a cylinder containing a suitable liquid which liquid was, by means of a piston and convenient means for operating the same, driven and drawn through tubes to cylinders carrying means for 25 operating drain cocks connected in a suitable manner to the locomotive cylinders.

The means for operating the drain cocks or valves consisted of a piston, traveling at right angles to the axis of these valves or 30 cocks and their stems, the forward, or operative, ends of which were cam like in form and which engaged and lifted or lowered the valves as it might be desired to open or close them. A spring engaged the forward end of the valve operating piston which 35 was compressed upon a forward movement of the piston and which assisted in returning this piston to its first position where the liquid to its rear was sucked out preparatory to 40 closing the valves.

In the operating of the device to lift the drain cocks not only the friction between the stems of the drain cock valves and the cam like ends of the operating piston had to be 45 overcome but also more or less power was consumed in compressing the springs engaging these pistons. These faults, while not so serious as to make the invention valueless, are more or less serious and the present invention is designed to obviate them.

In the drawing which accompanies this, a diagrammatic view of my present invention is shown.

a is an operating lever pivoted at *b* and

carrying a detent *c* adapted to engage with 55 a notched segment *d* in a usual and well known manner. To the lower end of the lever *a* is pivotally secured one end of a rod *e* the other end of which is secured to a piston *f* carried in a cylinder *g*. This part of my 60 device is precisely similar to a like part described in my former application.

To the forward end of the cylinder *g* is connected a pipe *h* which leads to one end of a cylinder *i* which carries a piston *j* fitted 65 with a cup washer *k* and suitable rings *l* of the usual construction.

m is a partition, carried by bridges *n* which are carried by the head proper *o* of the cylinder *i*, which closes off the cylinder above the 70 piston *j*.

p is a steam pipe or nipple adapted to be secured to the cylinder to be drained in a well known manner.

r is a union by means of which the nipple 75 *p* is removably connected to the cylinder *i*.

s is a valve, within nipple *p*, which is seated at *t* and furnished with a stem *u* which passes through partition *m* and which is adapted to be engaged by a projection *v* on 80 the upper end of piston *j*.

w is a drain hole in the side of the cylinder *i* above partition *m*. *x* a drain hole in the side of the cylinder below partition *m*.

y is a spider or stop in the nipple *p* above 85 the top of the valve *s*.

The cylinder *g*, the pipe *h*, and all connections leading therefrom to the bottom of cylinder *i* are filled with a liquid, with a non-freezing liquid or oil if the apparatus is to be 90 used in a cold climate. If it be desired to open the valve *s* to permit the escape of any liquid that may collect in pipe or nipple *p*, the lever *a* is operated so as to cause the rod *e* to advance the piston *f* in cylinder *g*, this 95 causes the liquid in this cylinder and in the pipe *h* to be forced into the cylinder *i* under the cup washer *k* of the piston *j* and this causes this latter piston to rise and to engage and lift the valve stem *u* which unseats 100 the valve *s* permitting any liquid that may be above it to pass through it and to pass out through orifice *w*.

To close the valve *s* the piston *f* is drawn back in cylinder *g* causing the liquid beneath 105 the piston *j* to return to pipe *h* and cylinder *g* and the piston *j* to fall when the valve *s* will reseat closing off the pipe or nipple *p*.

To facilitate and insure the complete draining of the cylinder *i* above the partition *m* the top of this partition is made convex and the drain hole *w* is on a line therewith.

5 The drain hole *x* below the partition *m* affords escape for any liquid that may leak past the valve stem *u* or past the piston *j*.

In the apparatus above described springs have been completely eliminated and friction 10 has been reduced by placing the piston *j* and the valve *s* in axial alinement.

Having thus described my invention I claim as new and desire to secure by Letters Patent:—

15 1. In a valve operating means, in combination, a valve, a stem carried by or engaging said valve, a cylinder divided into two parts by a partition through which said stem passes the sides of said cylinder being 20 furnished above and below said partition with perforations, a piston in the lower compartment of said cylinder having a movement in the direction of movement of said valve, a liquid carrying pipe one end of which 25 communicates with said cylinder beneath said piston and the other end with a hydraulic cylinder, said latter cylinder, a piston

in said latter cylinder, and means for operating said piston.

2. In a valve operating means, in combination, a valve, a stem or rod carried by or engaging said valve, a cylinder having an outlet in its side, a partition in said cylinder beneath said outlet through which partition said stem or rod passes, a piston in said cylinder beneath said partition, a liquid carrying pipe one end of which communicates with said cylinder beneath said piston and the other end with a hydraulic cylinder, said latter cylinder, a piston in said latter cylinder, and means for operating said piston. 30 35

3. In an apparatus of the character described, in combination, a cylinder having two outlets in its side, a partition across said cylinder between said outlets, a valve above 45 said partition, a valve stem passing through said partition, a piston below said partition, and means for introducing and withdrawing a liquid to or from said cylinder beneath said piston. 40
